UNITED STATES PATENT OFFICE.

FRANK I. JOYCE, OF DAYTON, OHIO.

HEAD FOR LIFTING-JACKS.

1,137,491.

Specification of Letters Patent. Patented Apr. 27, 1915.

Original application filed January 27, 1912, Serial No. 673,901. Divided and this application filed April 14, 1914. Serial No. 831,761.

To all whom it may concern:

Be it known that I, FRANK I. JOYCE, a citizen of the United States, and a resident of the city of Dayton, in the county of Montgomery and State of Ohio, have invented 5 certain new and useful Improvements in Heads for Lifting-Jacks, of which the following is a full, clear, and exact description, reference being had to the accompanying 10 drawings, forming a part of this specification.

This is a divisional application of my application filed January 27, 1912, for improvements in lifting jacks, Serial No. 15 673,901. The features of the jack head which form the subject matter of this application have relation particularly to the reduction to a minimum of the friction between the screw and the load of a screw 20 jack, by introducing a hydraulic support for the load. Generally the hydraulic support for the load is applicable to any jack, as will be obvious as hereinafter developed.

The several features of the invention herein 25 and the various advantages resulting from their use conjointly or otherwise will be apparent from the following description and claims.

In the drawings, the figure is a side elevation of my improved jack showing the head 30 in central vertical section.

The jack to which I have applied my improved head, and to which form of jack the new head is especially valuable, is a screw 35 jack, having a standard 1, screw 2, nut 3 in the standard screwthreaded to receive the screw, beveled gear 4 on the screw and beveled gear 5 in mesh with the first gear. The beveled gear 5 is carried on a shaft 6, with 40 a crank 7 on the end journaled in a bearing 8 bolted to the housing 9. This housing is slidably mounted on the standard and is raised when the screw is turned by means of the crank 7 and the gears.

45 On the beveled gear 4 of the screw of the jack is a bored, upwardly extending hub 23 which has a bearing and revolves in the bearing surface 24 of the cap 25, which cap is screwed into the upper end of the housing 50 9, which completes the housing for the jack.

Seated in the cylindrical bore 26 in the hub 23 is the ram 27. This ram extends

above the cap 25 to take the load, and at its lower end is provided with the hydraulic cup packing 28 held in place by the packing 55 ring 29 and packing nut 30, and also with a lock screw 31 to offset the tendency to unscrew. The ram 27 is cored out to form a reservoir 32 which opens into the cylindrical space 26 in the hub 23 of the crown gear 60 through the passage 33 normally closed by the spring-pressed valve 34. The reservoir 32 is closed by the screw plug 35, provided with the air vent 36, normally closed by the downwardly opening spring-pressed valve 65 37, in order to allow air to be drawn into the reservoir as the oil therein is drawn out, but to prevent the oil from escaping as the jack is thrown around. The ram is also supported by a conical spring 38 seated between the 70 base of the ram and the bottom of the reservoir 26. A conical bearing 39 is also provided to engage the conical seat 40 in emergencies when the oil has been allowed to run out of the reservoir. A roller bearing 41 is 75 also provided interposed between the upper surface of the hub 23 and the plate 42 underneath the cap 25 for the purpose of holding the gearing in proper mesh and to take the load when the ground lift 43 is being 80 used.

The cylindrical space 26 and the reservoir 32 are filled with oil, so that the ram 27 will be supported by the oil in the space 26, and the pressure when the ram carries the load 85 will be borne by the oil, while the hub 23 will be free to rotate with the gearing. There will be some slight leakage while the cup packing is expanding to take the load, and the ram will therefore settle slightly. 90 When the jack is relieved from the load, the coiled spring 38 will raise the ram to its proper adjustment, and the partial vacuum thus produced will force the oil from the reservoir 32 into the cylindrical space 26, to 95 replace what has passed the packing, while taking the load, while the air vent 36 will open to relieve the vacuum in the reservoir 32. In this way, it will be evident that a very perfect antifriction thrust bearing is 100 provided for the screw when subjected to the load.

It is evident that this head could be used in a lever jack where there is no housing

such as the housing 9 and 25, to be raised and lowered. No illustration of this has been deemed necessary because, if the top portion 25 and the rollers 41 were to be removed in the figure, the head thus formed would then be in shape to be used on a lever jack.

The reason for selecting the screw jack for illustration of the use of the improved jack 10 head is because the functions of the head in relieving parts from strain are most useful for this kind of jack.

Having thus described my invention, what I claim as new and desire to secure by Letters Patent, is:—

1. In a lifting jack, a standard, a member to be raised, a raising means, a socket on the member to be raised, a ram to engage the load seated in the socket, and a liquid cushion in the socket for the base of the ram to form an anti-friction thrust bearing for the raising means, with an oil reservoir in the ram, and a passageway therefor for the socket to maintain the liquid supply and 25 a valve normally to close the passageway adapted to open to permit passage of oil upon release of the load.

2. In a lifting jack, a standard and a lifting screw mounted therein, a ram to engage 30 the load with a socket in the head of the

screw within which the ram is seated, and a liquid cushion in the socket for the base of the ram to form an anti-friction thrust bearing for the screw, with an oil reservoir in the ram, and a passageway therefor to 35 the socket to maintain the liquid supply and a valve normally to close the passageway adapted to open to permit passage of oil upon release of the load.

3. In a lifting jack, a standard and a lifting screw mounted therein, a ram to engage the load with a socket in the head of the screw within which the ram is seated, and a liquid cushion in the socket for the base of the ram to form an anti-friction thrust bearing for the screw, with an oil reservoir in the ram, and a passageway therefor to the 40 socket to maintain the liquid supply and a valve normally to close the passageway, a spring bearing between the base of the 45 socket and the bottom of the ram to return the ram to normal position upon leakage of the liquid from the socket and to permit the liquid supply valve to open to renew the liquid in the socket.

FRANK I. JOYCE.
